UNITED STATES PATENT OFFICE.

BERNARDO MARTINOJA, OF NEW YORK, N. Y.

SELF-LOCKING BOX.

1,010,289.

Specification of Letters Patent. Patented Nov. 28, 1911.

Application filed August 25, 1910. Serial No. 578,939.

To all whom it may concern:

Be it known that I, BERNARDO MARTINOJA, a subject of the King of Italy, and a resident of the borough of Manhattan, city, county, 5 and State of New York, have invented certain new and useful Improvements in Self-Locking Boxes, of which the following is a complete and concise description, reference being had to the accompanying sheet 10 of drawing, which forms a part thereof.

My invention relates to certain improvements in so-called self-locking boxes which are designed for the reception of packages or other household necessities that are customarily delivered at the door-step of the premises, and it is the object of my invention to provide a box or receptacle for the reception of such commodities which is simple in construction, effective in operation 20 and inexpensive in cost of manufacture.

For a full understanding of the invention, reference is to be had to the following description and accompanying drawings, in which:

25 Figure 1 is a view in side elevation partly broken away, of the receptacle showing the features of my invention. Fig. 2 is a vertical sectional view thereof showing the same with a milk bottle placed therein. Fig. 3 is a front view of the lower portion of Fig. 1 showing the door open. Fig. 4 is a sectional plan view taken on line *a—a* of Fig. 1. Fig. 5 is a plan view of the locking slide or wedge.

30 35 I have illustrated a box-like receptacle comprising a base —A—, sides —D—, top —M— and door —F—.

—O— is a bar permanently secured to the door or support, to which the whole device 40 is intended to be attached.

—O'— is a bar placed beneath the lid —M— of the receptacle across its inner edge, and is of such size and proportion as to fit within a mortise in the cross-bar 45 —O—. At the lower end a bolt —P— and a lock-slide —R— form the means for securing the box at this point to the main door or support.

Within the receptacle I provide a false 50 bottom —B— pivoted at —C—, and beneath

the same is provided a spring member —E— which normally bears against the under side of the false bottom —B— and tends to hold it in raised position. The door —F— which is pivoted to the top and 55 bottom of the receptacle at —G— is provided at its lower portion and near the lower pivot point with an aperture or slot —I—. When the door is closed, the slot —I— is filled up by the piece —N— which 60 is attached to the side of the receptacle.

The operation of the device is as follows:— When the box is empty and no weight is resting upon the false bottom —B—, the spring —E— raises it up to a 65 position where it is opposite the slot —I— in the door —F—, in which position the door may be opened freely. But when a weight such as a milk bottle or other article is inserted upon the false bottom —B— the 70 latter is depressed, and when the door —F— is closed the false bottom —B— drops and the front edge abuts against the lower portion —L— of the door, thus locking it, as shown in Fig. 2, so that it cannot be opened 75 again until the contents have been removed and the false bottom —B— has moved up opposite the slot —I—, as shown in Fig. 1.

In order to remove the bottle or package within the receptacle, it is necessary to draw 80 the lock latch —R—, withdraw the bolt —P—, raise the receptacle bodily until the cross-bar —O'— is disengaged from the mortise of the cross-bar —O—, when the whole may be lifted clear and removed from 85 the door or support —X—. Thus access 90 may be had to the interior of the receptacle from the rear.

I do not wish to be limited to the application of my invention to a box of the character described, as the same may be and is applicable to controlling doors of houses and other analogous uses. Nor do I limit myself to the exact design, proportion, arrangement or specific details shown, as these 95 may be modified without departing from the spirit of my invention; but

What I do claim as new herein and desire to secure by Letters Patent, is:—

The combination of a swinging door pro- 100

vided with a cut-out portion at its lower extremity; a spring pressed pivoted bar or plate, one end or edge of which is adapted to aline with the cut-out portion of the door when said door is open, said bar or plate being adapted when under pressure to engage the lower extremity of the door when the latter is closed; and a rigid member adapted to

fill the cut-out portion of the door when closed.

In testimony whereof I affix my signature in presence of two witnesses.

BERNARDO MARTINOJA.
